UNITED STATES PATENT OFFICE.

FREDERICK ROEHN, OF CHICAGO, ILLINOIS, ASSIGNOR TO THE SCHOLL MANUFACTURING COMPANY, OF CHICAGO, ILLINOIS, A CORPORATION OF NEW YORK.

ARCH-SUPPORT.

1,784,816.

Specification of Letters Patent.

Patented Dec. 14, 1915.

Application filed May 1, 1915. Serial No. 25,315.

To all whom it may concern:

Be it known that I, FREDERICK ROEHN, a citizen of the United States, residing at Chicago, in the County of Cook and State of Illinois, have invented certain new and useful Improvements in Arch-Supports, of which the following is a specification.

My invention relates to improvements in arch supports, and in some of its features 10 more particularly, to an appliance for the relief or cure of breaking down of the transverse arch of the human foot.

In the treatment of this foot ailment, that involves a dropping of the head of one or 15 more of the metatarsal bones with consequent disturbance of the metatarsal-phalangeal articulation, it is important that restorative pressure be applied particularly to the metatarsal bone associated with the affected joint, and also it is highly beneficial 20 to afford support to the instep arch in general for effective distribution of the weight of the wearer, supplementing the restorative pressure adjacent to the affected joint.

One of the salient objects of my invention 25 is to provide a construction that is readily adjustable for proper location of pressure to secure the most effective treatment of such foot trouble.

Another object of my invention is to provide a device which is simple, cheap, 30 easily constructed, and quick to get off of, and capable of ready replacement and repair of the part that becomes applied to the affected toe, or to replace same if worn or strengthened the development of the cure.

In the drawings wherein I have illustrated an embodiment of my invention Fig. 1 is a bottom elevation of an instep arch 40 support end of my invention. Fig. 2 is a transverse section on line 2-2 of Fig. 1. Fig. 3 is a transverse section on line 3-3 of Fig. 1. Fig. 4 is a longitudinal section on line 4-4 of Fig. 1. Fig. 5 is a perspective 45 detail of the adjustable arm, and Fig. 6 is an enlarged detail of a pressure pad detached and inverted.

In the drawing, Fig. 1 illustrates an arch plate, 50 preferably of metal, such as German silver or aluminum, that is partially longitudinal and lateral curvilinear for a proximate conformati-

on to the plantar surface of the human foot between the heel and ball thereof, said plate being preferably arranged to affect a rear bearing in the shoe, as at 11, adjacent the bearing of the wearer's heel, and a front bearing 12 at about the rear portion of the ball of the foot somewhat in rear of the metatarsal-phalangeal articulations. Connected with this arch plate is a cover piece 55 13 preferably made of leather and secured to the plate as by rivets 14. Such cover-piece is shaped to conform to the shoe and to extend along the sole and shank thereof from the heel to a point substantially conforming 60 to the bases of the toes. In addition to giving comfort in use, such cover piece materially assists in locating the appliance in relation to the wearer's foot, although the arch-plate, seeking naturally the part of the 65 foot to which it most nearly conforms in shape, prevents any such shifting of the leather as would tend to curl it or wrinkle it.

Supplementing the metal arch plate, and adjustable relative thereto, I provide a metallic arm 16 that carries at its forward end a pressure pad 17 which is intended to be located beneath the cover piece 13 to provide a hump for exerting restorative pressure on the affected metatarsal bone or bones. Such 70 pad tends to lift the affected joint or joints to proper position and to prevent imposition of weight, in walking, upon the heads of the fallen metatarsal bones.

In the specific construction shown the 75 arm 16 is a thin metal strip, preferably relatively narrow and flexible enough for easy conformati-

on to the shape of the arch plate and shoe. The strip 16, as shown in Fig. 5, is

provided near its rear end with a pivot post 19 having a cross head 20, and also it carries

an upright latching pin 21 and a fastener

stud 22 that may be constructed after the

fashion of the well known glove fastener

stud. The plate 10, for coaction with this

arm, is provided with a slot 25 to receive the

pivot post 19 and with two or more rows of

holes 26 to receive the pin 21. Upon the

fastener stud 22 is detachably mounted the

pad 17, preferably made of leather or rub-

ber, appropriately shaped in generally

platy-convex form, and provided on its

underside adjacent its highest point with a

spring socket 27 complementary of the stud

22. This platy-convex pad preferably is

long enough to overlap at its rear end the

forward bearing edge 12 of the plate 10 so as to make a smooth tapering joint therewith that will not be uncomfortable to the wearer. Of course in size and in contour the pad may be varied so that more than one metatarsal bone may be supported, if desired, and so that pressure may be spread or localized as the needs of the individual case may require.

- 10 It will be apparent that in assembling the structure the arm 16 is applied to the plate by turning it at right angles to its intended position so that the parallel sided head 20 may slip through the slot 25, and then the 15 plate is pivotally turned to working position and its pin 21 is fitted in any one of the openings 26 in the plate, the slotting of the plate for reception of the pivot post 19 enabling the arm to be adjusted forward and 20 backward to register with either of the lines of openings, and its pivotal movement with respect to the plate slots enabling its pin 21 to be brought into engagement with any desired one of the holes. The pad 17 in turn 25 may be rotarily adjusted to any desired position so as to bring its highest convexity into just the position to give the greatest ease to the wearer and as the pad becomes unduly compacted, or change in the condition 30 of the foot of the wearer necessitates different pads, the substitution of new pads may be made.

It will be apparent to those skilled in the art that many changes in details of construction might be made in the embodiment of my invention without departure from the spirit of the invention and within the scope of the appended claims.

Having described my invention what I claim is:

1. In an arch support the combination of a metallic arch supporting plate, an arm carried by and adjustable to different positions with respect to said plate and having an end protruding beyond the plate, and a 45 pad structure carried by the extremity of said arm.

2. In a device of the character described the combination of an arch plate, an adjustable arm, and a pad, said pad carried by the 50 extremity of said arm beyond the plate, and said arm and plate having coöperating means for longitudinal and pivotal adjustment of the arm upon the plate and coöperating means for fastening the arm in selected position of longitudinal and pivotal adjustment.

3. In a device of the character described the combination of a metallic arch plate, a 55 flat arm therebelow protruding beyond the arch plate end and adjustable with respect to the arch plate, and a pad, carried by the protruding end of the arm, overlapping the edge of the arch plate.

4. In a device of the character described, 60 the combination of a metallic arch plate, a flat arm carried by the arch plate and adjustable relative thereto, and a detachable pad carried by the arm.

In testimony whereof I hereunto set my 70 hand in the presence of two subscribing witnesses.

FREDRICK ROEHN.
